UNITED STATES PATENT OFFICE

2,518,547

MANUFACTURE OF SHOES

Joseph A. Hill, Newburyport, Mass.

Application July 23, 1947, Serial No. 762,914

4 Claims. (Cl. 36—19.5)

1

This invention relates to an improvement in footwear and its principal objects are to provide a shoe or the like article of footwear which is of strong and durable construction but extremely flexible and possessing a high degree of wearing comfort, and to provide an efficient and economical method of manufacturing such a shoe.

Further objects relate to various features of construction and the method of manufacture and will be apparent from a consideration of the following description and the accompanying drawings, wherein:

Fig. 1 is a plan view of the outer face of an insole having its forepart marked to delineate the line of application of the reinforcing elements;

Fig. 2 is a view similar to Fig. 1 but showing the reinforcing elements applied;

Fig. 3 is a view of the inside of a shoe upper having the lasting allowance at its forepart marked to correspond with the markings on the insole;

Fig. 4 is a fragmentary perspective showing the manner in which the shoe upper and insole are connected prior to lasting;

Fig. 5 is a side elevation of the lasted shoe;

Fig. 6 is an enlarged section on the line 6—6 of Fig. 5;

Fig. 7 is a side elevation of a completed shoe constructed in accordance with the present invention;

Fig. 8 is a top plan view of the shoe shown in Fig. 7 with the forepart broken away to show the appearance of the inside; and

Fig. 9 is an enlarged section on the line 9—9 of Fig. 7.

In accordance with the present invention a suitable sock-lining or insole material, such as leather, a cork-leather or a cork-fabric composite, is dinked or cut out to provide either a full length, a three-quarter or a half-length insole or sock-lining which, if desired, may be provided with a fibre or leather reinforcing shank tuck. The insole, however produced, is preferably provided with markings along the opposite marginal portions of the underside of its forepart, these markings being spaced inwardly from about $\frac{1}{8}$ of an inch to one inch, a preferred spacing being about $\frac{1}{2}$ inch in from the adjacent edge of the forepart, and they may extend from adjacent the toe portion to the rear of the ball portion, or to the rear of the shank portion if extra reinforcement is desired.

The inner longitudinal edges or marginal portions of a pair of reinforcing strips or tapes are stitched, stapled or otherwise secured to the underside of the opposite marginal portions of the insole member along the lines defined by the above-mentioned markings. The length of the reinforcing strips preferably corresponds to the length of the markings and the width of the

2

strips may vary from about one-eighth inch to one inch, depending upon the spacing of the marginal markings from the edges of the insole; for example, a one-half inch marginal marking on the insole would preferably require a three-eighths inch tape or strip, thereby leaving a one-eighth inch clearance. Although a plain fabric reinforcing tape may be used, it is preferable to employ a tape having a thermoplastic or other suitable adhesive along its outer marginal portion on the side facing the insole.

After the reinforcing strips have been applied to the opposite marginal portions of the insole, as above-described, the latter is thus ready for assembly with an upper which may be either a closed toe and/or back, an open toe and/or an open back, or any other style, and in any case the upper may be prepared in accordance with conventional practices. In order to insure proper attachment of the insole and upper, the lasting allowance at the opposite forepart portions are marked to correspond with the markings of the insole, i. e., the lengths of the markings are preferably the same as those on the insole and likewise the spacings of the markings from the outer edge of the lasting allowance preferably correspond with the spacings on the insole, but in any case the spacing is sufficient to insure adequate lasting allowance. The outer edge or marginal portions of the reinforcing strips are stitched, stapled or otherwise secured to the opposite marginal portions of the marked lasting allowance along the lines defined by the markings, thus providing a fitted upper with an attached insole.

The assembled upper and insole are then applied about a last, during which operation the reinforcing strips are folded longitudinally on themselves so that the folded strips are interposed between the lasting allowance of the upper and the marginal portions of the insole. Where, as is usually preferred, a thermoplastic adhesive reinforcing tape is used, sufficient heat may be applied to the inturned lasting allowance of the lasted shoe prior to the outsole attaching operation, thereby to activate the adhesive to cause the body of the tape to become adhesively united to the marginal portions of the upper, thus insuring a more reliable attachment of the reinforcing tape thereto. The lasted shoe may then be finished in the usual manner.

Referring to the accompanying drawings wherein I have illustrated what is now considered a preferred procedure for making an oxford-type shoe, the numeral 1 designates a full length laminated insole composed of an inner layer of suitable fabric 2 adhesively united to an outer layer of sheet cork 3, as shown in Figs. 1 and 9. The opposite marginal portions of the underside of the forepart of the insole are marked as shown at 5 and 6 in Fig. 1 and the inner longitudinal

edges of a pair of reinforcing tapes 10 and 11 are secured to the insoles along the markings by a single line of stitching 12 which, as shown in Figs. 2 and 8, extends from the toe end of one strip across an arcuate path at the rear ball portion of the insole to the toe end of the other strip. The tapes 10 and 11 are provided with a layer of thermoplastic adhesive 14 (Fig. 2) along their outer marginal portions and the tapes are so applied that the adhesive layer 14 faces the outer side of the insole.

The opposite marginal portions or lasting allowance of an upper 15, prepared in accordance with conventional practice, are provided with markings 16 and 17 which correspond respectively with the markings 5 and 6 of the insole. The upper and insole thus prepared are assembled so that the outer longitudinal edges of the reinforcing tapes 10 and 11 are applied to the marked portions of the upper and while thus positioned the outer longitudinal edges of the tapes are stitched to the marked parts of the upper by the lines of stitching 20 and 21, as illustrated in Figs. 4, 6 and 9.

The assembled insole and upper are then applied about a last L, as illustrated in Figs. 5 and 6, after which sufficient heat is applied either to the tapes 10 and 11 or the inturned lasting allowance to cause the thermoplastic coating 14 adhesively to unite the contiguous portions of the lasting allowance of the upper with the body of the tape. During the lasting operation the tapes are folded longitudinally upon themselves and the folded tapes are interposed between the lasting allowance of the upper and the marginal portions of the insole, as shown in Fig. 9. The usual padding or filler 25 (Fig. 9) may then be applied to the forepart cavity as defined by the inturned lasting allowance, after which an outsole S and heel H may be applied in accordance with conventional practice.

The completed shoe (Fig. 7) has the external appearance of a conventionally lasted shoe such as a McKay, and its interior, as shown in Fig. 8, has the relatively flat and smooth characteristics of the so-called California shoe, but does not require the use of a sock lining. Since a shoe constructed in accordance with the present invention embodies the use of a relatively flexible insole securely attached to the upper, a high degree of flexibility and wearing comfort is assured. Moreover, the strips of tapes firmly anchor the upper and insole together and not only reinforce these parts but also prevent the margins of the insole from curling up after the shoe has been worn. It will be noted that the construction permits the use of relatively weak insole material, such as sheet cork, light fabric, skived leather, etc., without the necessity of providing reinforcements for these elements, and that the lasting of the assembled upper and insole cause an outward pull which overcomes any danger of buckling the insole.

While I have shown and described one desirable type of shoe and method of making the same, it is to be understood that this disclosure is for the purpose of illustration and that various changes and modifications may be made without departing from the spirit or the scope of the invention as set forth in the appended claims.

I claim:

1. The method of making a shoe which comprises providing an insole having permanently secured thereto reinforcing strips at the opposite marginal portions of the underside of the fore-

part, securing the outer longitudinal marginal portions of said reinforcing strips to corresponding parts of the inner face of the lasting allowance of an upper, lasting the assembled insole member and upper so as to cause said reinforcing strips to fold longitudinally upon themselves, the folded reinforcing strips being interposed between the lasting allowance of the forepart of said upper and the marginal portions of the forepart of said insole member, and thereafter completing the shoe.

2. The method of making a shoe which comprises providing an insole having permanently secured thereto reinforcing strips at the opposite marginal portions of the underside of the forepart, the reinforcing strips having an adhesive coating along their outer marginal portions on the side facing the insole, securing the outer longitudinal marginal portion of said reinforcing strips to corresponding parts of the inner face of the lasting allowance of an upper, lasting the assembled insole member and upper so as to cause said reinforcing strips to fold longitudinally upon themselves, the folded reinforcing strips being interposed between the lasting allowance of the forepart of said upper and the marginal portion of the forepart of said insole member so that said adhesive coating unites the body of the reinforcing strips to the lasting allowance, and thereafter completing the shoe.

3. The method of making a shoe which comprises providing an insole having permanently secured thereto reinforcing strips at the opposite marginal portions of the underside of the forepart, the reinforcing strips having a thermoplastic adhesive coating along their outer marginal portions on the side facing the insole, stitching the outer longitudinal marginal portion of said reinforcing strips to corresponding parts of the inner face of the lasting allowance of an upper, lasting the assembled insole member and upper so as to cause said reinforcing strips to fold longitudinally upon themselves, the folded reinforcing strips being interposed between the lasting allowance of the forepart of said upper and the marginal portion of the forepart of said insole member, so that said adhesive coating unites the body of the reinforcing strips to the lasting allowance, and thereafter completing the shoe.

4. A shoe comprising an insole member, an upper, and reinforcing strips having one of their longitudinal edges secured to the opposite marginal portions of the forepart of said insole member and the other longitudinal edges of said reinforcing strips being secured to the inturned margins at the opposite sides of the forepart of said upper, said reinforcing strips being folded longitudinally upon themselves and the folded reinforcing strips being interposed between said inturned margins of the upper and the marginal portions of said insole member, thereby to anchor the insole member to said inturned margins and provide a reinforcement for these parts.
